UNITED STATES PATENT OFFICE.

JOSEPH LESLIE MUSGRAVE AND RICHARD GODFREY CRITTALL, OF LONDON,
ENGLAND.

APPARATUS FOR CONSTRUCTING REENFORCED-CONCRETE STRUCTURES WHICH CONTAIN IMBEDDED MEANS FOR CIRCULATING A HEATING OR COOLING MEDIUM.

Application filed September 20, 1923. Serial No. 863,862.

To all whom it may concern:

Be it known that we, JOSEPH LESLIE MUSGRAVE and RICHARD GODFREY CRITTALL, subjects of the King of Great Britain, residing, 5 respectively, at 43 Bloomsbury Square, London, W. C. 1, England, and at 43 Bloomsbury Square, London, W. C. 1, England, have invented new and useful improvements 10 in apparatus for constructing reenforced-concrete structures which contain imbedded means for circulating a heating or cooling medium, of which the following is a specification.

This invention refers to the heating and 15 cooling of buildings, and has reference to buildings in which the supporting columns, walls, floors and ceilings are formed of reenforced concrete.

Reenforced concrete columns, walls and 20 the like are built in situ, this being accomplished by first constructing a "shuttering" or wooden structure or mould inside which the metal rods or other material used to reinforce the concrete are placed in position, 25 after which the concrete mixture is poured or thrown in.

Now according to this invention we place 30 at suitable intervals apart in the interior of the "shuttering" either on one or more of its sides pipes through which the heating or cooling fluid circulates. As for example in the formation of a reenforced concrete column we may place pipes on all sides in the interior of the "shuttering". These 35 pipes which are connected or prepared to be connected to headers are held in position against the inner surface of the "shuttering" by metal bands or ties the ends of which project through openings in the 40 "shuttering" to which they are secured by wedges, keys or other means.

After the mould or "shuttering" has been filled and the concrete has set the wedges or keys which secure the clips to the "shuttering" 45 are driven out and the "shuttering" removed leaving the outer surface of the pipes and the projecting ends of the clips exposed. When these projecting ends of the clips have been sawn off close to the 50 surface such surface is covered with plaster or other suitable material in the usual manner.

To further secure the pipes in position in the concrete clips or fasteners may be at-

tached to or slipped over the pipes before 55 the "shuttering" is filled with concrete so that these become cast in position.

The invention is illustrated on the accompanying drawing.

Fig. 1 is a plan view showing a reenforced 60 concrete column in the course of erection in situ according to this invention.

Fig. 2 is a broken plan view of Fig. 1 showing the "shuttering" removed after the 65 keys or wedges have been driven out.

Fig. 3 is an enlarged broken sectional plan of a portion of a wall or column constructed according to this invention.

A represents the "shuttering" or wooden 70 structure or mould, B the metal reenforcing rods, D the pipes through which the heating or cooling fluid circulates, d^1 the metal bands or ties which pass through holes in the "shuttering" to hold the pipes in position against its inner surface, d^2 the wedges 75 or keys by which the bands are secured to the "shuttering", and d^3 the headers to which the ends of the pipes are connected.

At Fig. 1 we have shown how a reenforced 80 concrete column, from the four surfaces of which heat or cold radiates, is built up in situ. The "shuttering" A is constructed in the usual known manner and in the interior of the four sides we place the pipes D which are held in position by the metal bands d^1 , 85 holes being made in the "shuttering" to permit the ends of said bands to pass through. Holes are also made in the ends of the bands d^1 to enable them to be secured by the wedges d^2 to the "shuttering".

After the reenforcing rods B have been 90 placed in position the "shuttering" is filled with the concrete mixture. When the concrete is set the wedges d^2 are driven out and the "shuttering" removed, the outer surface of the pipes D and the projecting ends of the clips d^1 being exposed, as clearly 95 shown by Fig. 2. The projecting ends of the clips are now sawn off close to the surface of the column, such surface being then covered over preferably first with a material d^4 which is more or less heat conducting and then with plaster d^5 or tiles or other material, as shown by Fig. 3, from the 100 surface of which the heat or cold radiates. The heat conducting material and the plaster, when forming the finished surface, may be 105 reenforced with fabric or other material.

What we claim as our invention and desire to secure by Letters Patent is:—

1. The combination with a mold for defining the surface of a concrete building structure, of pipes to be used for the flow of a heating or cooling fluid therein in the completed building, for heating or cooling the interior of the building, and bearing against the inner surface of the mold so as to be imbedded in the concrete and leave said pipes exposed at the surface of the concrete when the concrete has set and the mold is removed, and means securing said pipes and mold together and supporting the
- 10 to be imbedded in the concrete and leave said pipes exposed at the surface of the concrete when the concrete has set and the mold is removed, and means securing said pipes and mold together and supporting the
- 15 pipes in place from the mold and capable of releasing the mold from the pipes when the concrete has set.

2. The combination with a mold for defining the surface of a concrete building

structure, of pipes to be used for the flow 20 of a heating or cooling fluid therein in the completed building, for heating or cooling the interior of the building, and bearing against the inner surface of the mold so as to be imbedded in the concrete and leave said 25 pipes exposed at the surface of the concrete when the concrete has set and the mold is removed, and clips engaging around said pipes and outwardly through the mold and clamping the pipes and mold together so as 30 to support the pipes in place from the mold and adapted to release the mold from the pipes when the concrete has set.

In testimony whereof we have signed our names to this specification.

JOSEPH LESLIE MUSGRAVE.
RICHARD GODFREY CRITTALL.
